(57) **CLAIM**

The ornamental design for a shaving razor cover, as shown and described.

DESCRIPTION

FIG. 1 is a front perspective view of a design of a shaving razor cover in a closed position showing my new design;
FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a bottom view thereof;
FIG. 8 is rear perspective view thereof;
FIG. 9 is a front perspective view of the shaving razor cover in an open position;
FIG. 10 is a front view thereof;
FIG. 11 is a rear view thereof;
FIG. 12 is a right side view thereof;
FIG. 13 is a left side view thereof;
FIG. 14 is a top view thereof;
FIG. 15 is a bottom view thereof; and,
FIG. 16 is rear perspective view thereof.

The dash broken lines shown illustrate portions of the shaving razor cover and form no part of the claimed design.
